UNITED STATES PATENT OFFICE

ROSWELL C. VAN SICKLE, OF WILKINSBURG, PENNSYLVANIA, ASSIGNEE TO WESTINGHOUSE ELECTRIC & MANUFACTURING COMPANY, A CORPORATION OF PENNSYLVANIA

COIL FOR CIRCUIT BREAKERS

Application filed August 9, 1927. Serial No. 211,687.

My invention relates to electric solenoids and more particularly to solenoids for operating circuit interrupters.

One object of my invention is to provide a solenoid that has a plurality of separate windings.

Another object of my invention is to provide a solenoid with a plurality of separate windings that may be interconnected with each other in different ways to vary their exciting ampere turns without having to change the voltage impressed upon them.

A further object of my invention is to provide a solenoid with separate windings that may be interchangeably connected so as to produce the same number of ampere turns under different supply voltages.

It has been necessary, heretofore, to employ a specific operating coil corresponding to the supply voltage in order to obtain the number of ampere turns required to actuate the circuit-breaker operating mechanism. It has, therefore, been necessary for a manufacturer to keep in stock a large number of coils for each operating mechanism. Furthermore, any one mechanism may be employed to operate circuit breakers of several different sizes, that is to say, a mechanism having a three-inch core may be employed to operate a single-pole 4,000 ampere breaker, a two-pole 2,000 ampere breaker, or a three-pole 800 ampere breaker.

It has been the practice, in the circuit interrupter art, to provide the closing mechanism with a coil capable of operating the circuit through a range of voltage varying from 72% to 112%. At the higher value, the circuit interrupter must not close with such violence as to result in the destruction of any of its parts while, at the lower value, the latching of the interrupter should be assured. As a coil cannot be designed to operate successfully over a larger range, it will be seen that for any one particular mechanism several coils must be designed for each interrupter size,

as the forces required to close the one, two and three-pole breakers will all be different. As the usual operating voltages range from 125 volts to 600 volts, the number of coils which the manufacturer must keep in stock 50 for each operating mechanism becomes quite large. It is in order to avoid this multiplicity of coils that I have invented the coil that is illustrated in the accompanying drawing, in which:

Figure 1 is a view, in elevation, of a particular embodiment of my invention;

Fig. 2 is a sectional view on the line II-II of Fig. 1;

Figs. 3 to 8 are diagrammatical views of some of the connections that may be made to the terminals shown in Fig. 1; and

Fig. 9 is a view, in elevation, of a circuit interrupter embodying a feature of my invention shown in Fig. 1.

My invention comprises, in general, a coil 1 that is of the usual type except that the windings therein contained are separate and may consist of wire of a single size or wires of different sizes, and all of them may be 70 uniform, as regards the number of turns, or they may be different in this respect.

In Figs. 1 and 2, each winding 17, 18 and 19 terminates at the surface of the coil in a pair of terminals. The drawing shows an upper pair 2 and 3 for winding 17, a middle pair 4 and 5 for winding 18, and a bottom pair 6 and 7 for winding 19. Each pair of terminals belongs to a winding so designed that it may be connected directly across a supply line of some standard voltage. By this construction, each winding may be employed to operate the circuit breaker separately, thus making possible the employment of the same solenoid with sources of several different voltages. Fig. 9 represents a connection of this character in which only the upper pair of terminals, 2 and 3 of winding 17, are employed.

In a coil of the above type that has actual-

ly been employed, the above described connection to terminals 2 and 3 results in producing a pull of 26,700 ampere-turns with 100 volts impressed. Fig. 4 shows a connection in which the windings 17 and the windings 18 are connected in parallel. This arrangement resulted in a magnetizing force of 46,400 ampere-turns with the same supply voltage. In Fig. 3, all of the windings are connected in parallel, thus producing a magnetizing force of 57,600 ampere-turns with the same supply.

Various other forms of connections, some of which are shown in Figs. 5, 7 and 8, may be employed that will produce strengths in the pull of the solenoid ranging from 11,200 ampere-turns to 57,600 ampere-turns. This variation is obtained by connecting the pairs of terminals in various ways; that is to say, 15 in series, as in Fig. 8; in parallel, as in Fig. 3; one in series with a pair of coils connected in parallel, as in Fig. 5, or one in parallel with a pair connected in series. The magnetizing force may further be varied by connections with all of the coils acting in the same direction or with one or more coils opposed magnetically to the others.

In this way, the resistance and effective number of turns of the solenoid aggregate are 20 varied, and thus many different numbers of ampere-turns may be obtained at a given impressed voltage. An operating mechanism equipped with a coil of this type may be employed to actuate a newly designed circuit 25 interrupter before the pull required to close it is definitely known, as an arrangement of the windings may readily be found which will provide the required magnetic force.

For the same reason that different pulls 30 may be obtained for a given source of supply by rearranging the connections of the different pairs of terminals, it will also be seen that my invention is useful in providing a winding having the same number of ampere 35 turns for different supply voltages. If it is desired to move the mechanism to a place where the source of energy to supply the operating solenoid will be different, or if it be desired to make a change in potential of the supply circuit, it will only require that the 40 connections of the various pairs of terminals be changed. This avoids the necessity of securing a new coil designed specifically for the new supply voltage.

In constructing a coil of this type, a proper 45 selection of the size of wire for each winding should be made so that the various connections thereof will result in a solenoid in which different numbers of ampere-turns 50 may be obtained in regular steps, covering a wide range. As a specific illustration of a set of windings which I have found to be of practical utility, the data sheet of a solenoid having the above characteristics is given below, in which is shown the terminal connec-

tions, the terminals with which the leads are associated and the resulting ampere-turns obtained when a 100 volt supply circuit is connected across the leads. In this solenoid the winding between terminals 2-3 has 1110 70 turns and 5.74 ohms resistance; that between terminals 4-5 has 782 turns and 4.97 ohms resistance; and that between terminals 6-7 has 875 turns and 9.8 ohms resistance.

Terminals connected together	Terminals connected together	Leads on terminals	Ampere-turns at 100 volts
2-4-6	3-5-7	2-3	57,600
2-4	5-6	2-3	46,400
2-4	3-7	2-3	40,500
2-6	3-7	2-3	37,900
2-4	3-6	2-7	36,300
2-5	3-7	6-7	34,500
4-6	3-7	6-7	30,900
2-4-6	5-7	2-7	28,400
2-5-6	3-7	3-4	27,100
		2-3	26,700
3-4		2-5	23,300
		4-5	19,700
2-4	3-5-6	2-7	18,500
3-4	5-6	2-7	17,400
2-5		2-7	16,600
5-6		4-7	14,100
		6-7	11,200

The above tabulation does not contain any case in which one or more coils are bucking the magneto motive force of another coil which would provide an addition to the above data.

It may be noted that, with this coil, it is possible to have two combinations giving the same total number of ampere turns but with different resistances and different numbers of effective turns. This means that the time 100 constant of the coil will be different for the two combinations. Therefore, it should be possible to vary the speed of closing of the breaker on this particular set of points, the one with the lower time constant closing 105 the breaker more rapidly because the current will build up in the coil in a shorter length of time.

Such a circuit breaker employed with my coil is shown in Fig. 9 wherein a main circuit 8, 9 is bridged by a single pole-unit 11 that is connected through an operating mechanism 12 to an armature 13 which moves the pole unit to closed circuit position. A core member 14 is associated with the armature 115 13 and is energized through the medium of the coil 1 that is connected to the supply circuit 15, 16. The armature, coil and core member may be employed to operate a plurality of pole units 8 on a polyphase circuit of 120 less current rating. The plurality of small pole units will require approximately the same pull when operated as that required by the single large pole unit.

It will thus be seen that I have devised a 125 solenoid that will be useful in the circuit-breaker art, since a coil thus designed is extremely flexible in application. A wide range of different pulls may be obtained with a given source of energy by merely changing 130

the connections to the various windings; or, alternately, the same pull may be obtained when employing supply circuits of different voltages by the reconnections of similar character. This is a great saving in time and money both to the manufacturer and to the consumer, as one coil may now be employed to take the place of a multiplicity of coils heretofore required.

10 It is to be understood that such changes in the form, arrangement, and connection of the component parts of my invention, may be made as shall fall within the scope of the appended claims.

15 I claim as my invention:

1. An actuating solenoid for a circuit interrupter having three separate windings each of a different size of wire, said windings each forming a separate circuit.

20 2. In an actuating device for a circuit breaker, a movable core member for actuating a plurality of single-pole circuit interrupters, a coil therefor having a plurality of separate windings, said windings being constructed so that they each produce a different number of ampere-turns when supplied from a source of the same voltage.

25 3. A solenoid for circuit interrupters having a plurality of separate windings, each of said windings being constructed so as to produce a number of ampere-turns different from that produced by each of the other windings and means for interconnecting the several windings.

35 4. A solenoid for actuating a circuit interrupter comprising a plurality of windings, each of said windings being of wire having a different resistance per turn, and having a separate electrical circuit, and means for connecting said windings in a plurality of different combinations, said means including a pair of external terminals for each of said windings.

40 5. A solenoid for actuating a circuit interrupter comprising a plurality of windings, each of said windings being of wire having a different resistance per turn, and having a different number of turns and a separate electrical circuit, and means for connecting said windings in a plurality of different combinations, said means including a pair of external terminals for each of said windings.

45 6. An actuating device including a movable armature and a magnetizing coil for moving said armature, said coil comprising a plurality of windings each having an independent electrical circuit and a pair of external terminals, and each of said windings being of wire of a different size.

50 7. An actuating device including a movable armature and a magnetizing coil for moving said armature, said coil comprising a plurality of windings each having an independent electrical circuit and a pair of external terminals, and each of said windings

being of wire of a different size and having a different number of turns.

55 8. An actuating device including a movable armature and a magnetizing coil for moving said armature, said coil comprising a plurality of windings each having an independent electrical circuit and a pair of external terminals, and each of said windings having a different number of turns.

60 9. An actuating device including a movable armature and a magnetizing coil for moving said armature, said coil comprising a plurality of windings each having an independent electrical circuit and a pair of external terminals, and each of said windings having a different number of turns.

65 In testimony whereof, I have hereunto subscribed my name this 3rd day of August, 1927.
